FAN OR BLOWER CONSTRUCTION

Bertrand A. Parkes and Ralph C. Parkes,
Philadelphia, Pa.

Application September 22, 1937, Serial No. 165,097

4 Claims. (Cl. 230—273)

Our invention relates to a new and useful fan or blower, and it relates more particularly to a self-contained construction which can be put in use wherever needed without in any way interfering with the construction of any machine or other appliance in connection with which it is to be used.

Our invention further relates to a fan or blower construction in which the actuating motor is mounted in a vertical, adjustable manner at a point relatively remote from the fan or blower element itself which also lends itself to vertical mounting and in which the action of the blower, in delivering air, is utilized to cool the bearings and other moving parts.

Our invention still further relates to a fan or blower unit which is capable of both vertical and horizontal adjustment thereby rendering it easily applicable at any desired point and permitting accurate alignment of the parts regardless of surface irregularities.

Our invention still further relates to a fan or blower construction which is reversible without any loss of capacity or efficiency.

Our invention still further relates to other novel features of construction and advantage all as will be seen from the annexed specification and the accompanying drawing in which:

Fig. 1 represents a view partly in side elevation and partly in section of a fan or blower construction embodying our invention.

Fig. 2 represents a view in front elevation of the motor support shown detached.

Figure 3 represents a fragmentary plan view of Fig. 2.

Referring to the drawing in which like reference characters indicate like parts, 4 designates an outer elongated hollow housing or frame or housing which is supported by the lateral flanges 6. 8 designates a vertical bracket which may be integral with or suitably secured to the inner elongated hollow housing 10, the latter being secured by the bolts 12 which are adjustable in the slots 14 to the outer or main housing 4. The vertical bracket 8 and horizontal housing 10 form an L-shaped structure as best seen in Fig. 1. To the vertical bracket 8 is suitably secured the motor 16, as by the bolts 18, engaging the holes 20.

In order to permit of vertical adjustment of the bracket 8 and motor 16 with respect to the frame 4 we provide the plates 24 secured by the bolts 25 to the inside walls of the frame or housing 4 (see Fig. 2), and we also provide the set screw 22 which bears upon the corresponding end of

the inner housing 10. Thus, with the screws 12 loosened, the inner housing 10 will be loosely positioned within the outer frame or housing 4 and it will be balanced or fulcrumed upon the plates 24. The inner housing 10 is then brought to the desired horizontal adjustment and the set screw 22 is turned in the proper direction to hold the inner housing 10 in the adjusted position whereupon the screws 12 are tightened to fasten the inner housing 10 to the outer frame or housing 4.

In order to insure proper tension on the belting 26, we provide the rod 28 which carries the cam 30 which is adapted to bear against the plate 32 secured to the housing 4 so that, by loosening the bolts 12 and turning the rod 28, the bracket 8 can be moved with respect to the housing 4, and, when the desired tension on the belting 26 has been attained, the bolts 12 are again tightened. The belting 26 travels over the multiple pulley 34 which turns the shaft 36 to actuate the fan blades 38 and 40. The shaft 36 is enclosed in a casing 42 and is centralized by the set screws 44 engaging the bearings 46. The casing 42 is provided with the lower openings 48 and the upper openings 50 to permit suction of air into and discharge of air from the casing 42 in the direction of the arrows in Fig. 1, thus cooling the pulley 34 and the bearings 46.

By assembling the fan proper at a distance from the actuating motor 16 we render our construction particularly adapted for use in connection with drying machines and the like in which it is desirable in the interests of efficiency to mount the fan or blower within the casing, 35 housing, or other inclosure 54 of a drying machine (diagrammatically illustrated in dotted lines), but in which it is not desirable to have the motor also within the casing due to the heat developed within the casing and the necessity of 40 maintaining the motor 16 as cool as possible. The bearings 46 are, as above pointed out, cooled by the supply of fresh air drawn through the main housing 4 at its outer extremity near the bottom of the motor 16, and the fan blades 38 and 40 are within the drying chamber proper. It is understood that the outer housing 4 and the inner housing 10 can be made of any desirable length either in one piece or in sections.

Having thus described our invention, what we claim as new and desire to secure by Letters Patent is:

1. A fan or blower construction comprising an L-shaped bracket, a motor carried by the vertical portion thereof, an elongated hollow housing,

- means within said housing for supporting the horizontal portion of said L-shaped bracket, there being horizontal slots in said housing, means passing through said slots and engaging said horizontal portion of said bracket for laterally adjustably securing the latter to said housing, means carried by said housing and acting on said horizontal portion of said bracket for vertically adjusting said motor, a vertical casing at the other 10 end of said housing, a fan shaft disposed within said casing and projecting downwardly into said housing, and driving connections leading from said motor through said housing to the lower end of said shaft for actuating the latter.
- 15 2. A fan or blower construction comprising an L-shaped bracket, a motor carried by the vertical portion thereof, an elongated hollow housing, means within said housing for supporting the horizontal portion of said L-shaped bracket in 20 balanced position, there being horizontal slots in said housing, means passing through said slots and engaging said horizontal portion of said bracket for laterally adjustably securing the latter to said housing, means carried by said housing and acting on said horizontal portion of said bracket for vertically adjusting said motor, a vertical casing at the other end of said housing, a fan shaft disposed within said casing and projecting downwardly into said housing, driving 25 connections leading from said motor through said housing to the lower end of said shaft for actuating the latter, there being ventilating holes in said vertical casing of said fan shaft, and a cam element carried by the vertical portion of said 30 L-shaped bracket and adapted to bear against a plate carried by said housing for tightening said driving connections.

3. A fan or blower construction for drying machines and the like comprising an elongated horizontal hollow housing, one end of said housing being disposed within the drying chamber of a drying machine, a fan assembly extending upwardly from said end of said housing, a bracket mounted for vertical and horizontal adjustment at the other end of said housing, a motor carried by said bracket, and driving connections extending from said motor through said housing to the lower 10 end of said fan assembly to actuate the latter, whereby said motor is disposed in the relatively cool air outside of said drying chamber and whereby the movement of said driving connections produces a stream of relatively cool air 15 through said housing and about said fan assembly.

4. A fan or blower construction for drying machines and the like comprising an elongated horizontal hollow housing, one end of said housing 20 being disposed within the drying chamber of a drying machine, a fan assembly including oppositely disposed fan blades extending upwardly from said end of said housing, a bracket mounted for vertical and horizontal adjustment at the 25 other end of said housing, a motor carried by said bracket, and driving connections extending from said motor through said housing to the lower end of said fan assembly to actuate the latter, whereby said motor is disposed in the relatively cool air 30 outside of said drying chamber and whereby the movement of said driving connections produces a stream of relatively cool air through said housing and about said fan assembly.
